UNITED STATES PATENT OFFICE.

WILLIS J. BICKFORD, OF NORTH ATTLEBOROUGH, MASSACHUSETTS.

DENTAL JAW-BRACE.

SPECIFICATION forming part of Letters Patent No. 323,627, dated August 4, 1885.

Application filed December 28, 1882. (Model.)

To all whom it may concern:

Be it known that I, WILLIS J. BICKFORD, of North Attleborough, in the county of Bristol and State of Massachusetts, have invented 5 a new and Improved Mouth-Prop for Dentists' Use, of which the following is a full, clear, and exact description.

My invention relates to devices used by dentists for keeping the mouth of a patient 10 open when gas is administered.

Reference is to be had to the accompanying drawings, forming part of this specification, in which similar letters of reference indicate corresponding parts in both the figures. 15 Figure 1 is a side perspective view of my improved mouth-prop. Fig. 2 is a longitudinal section of the same.

A tube, A, of suitable size and length, is fitted with a slide-pin, B, and the tube contains 20 a spiral spring, a, which tends to force the pin B outward, a screw-pin, b, or other suitable device, being applied to the tube to limit the elongation of the two parts. The outer end of the tube A and of the pin B are 25 provided with socket-pieces c, of suitable shape, in which are fitted blocks d, of rubber or other soft material, and the two opposite sides of the socket-pieces are formed to project above the rubber, so as to act in retaining 30 the device in place. This prop, after being put in place in the patient's mouth, is held firmly in position against the teeth by the spiral spring, and readily adapts itself to any

movement of the jaw. The prop is thus prevented from dropping out, and the mouth is 35 kept open wide enough for any operation. The prop is preferably made of metal plated with nickel or other metal, so that, while it possesses greater strength than the ordinary wooden peg, it is much smaller, and consequently 40 takes up less room. Further, it is much more cleanly than the wooden plug, cannot corrode or tarnish, and can be readily kept clean.

I am aware that it is not new to make a jaw-brace with a rigid middle part and elastic extremities, or of a rubber plug held in a shorter tube by a screw; but

What I do claim as new is—

As an improved article of manufacture, a 50 jaw-brace consisting of a tube, A, having a socket, c, for receiving an elastic block, d, the pin B, sliding within the tube, having a socket, c, for receiving an elastic block, d, the spiral spring a, within the tube below the pin 55 B, to force said pin outward, and a pin, b, for preventing the pin B from being thrown entirely out of the tube, substantially as set forth, whereby when said brace is in place in a patient's mouth the spring will prevent the 60 brace from being displaced should the mouth be opened to a greater or less extent.

WILLIS J. BICKFORD.
